A. E. VERRAL.
GAME APPARATUS.
APPLICATION FILED APR. 10, 1916.

1,190,488.

Patented July 11, 1916.

UNITED STATES PATENT OFFICE.

ARTHUR EDWARD VERRAL, OF TORONTO, ONTARIO, CANADA.

GAME APPARATUS.

1,190,488.

Specification of Letters Patent. Patented July 11, 1916.

Application filed April 10, 1916. Serial No. 90,165.

To all whom it may concern:

Be it known that I, ARTHUR EDWARD VERRAL, of the city of Toronto, in the county of York and Province of Ontario, Dominion of Canada, have invented certain new and useful Improvements in Game Apparatus; and I hereby declare that the following is a full, clear, and exact description of the same.

10 This invention relates to a game apparatus comprising a perpendicular barrier of substantially triangular or pyramidal shape, the inclined sides of which are stepped from approximately the base to the apex, each 15 step having a socket therein to receive a removable flag or marker which can be moved up or down the stepped sides during the progress of the game, and the base of which is apertured for the passage of projectiles from opposite sides of the barrier, which is maintained in an upright position 20 by suitable supports secured thereto.

For an understanding of the invention, reference is to be had to the following description and to the accompanying drawings, 25 in which:—

Figure 1, is a perspective view of the game apparatus; and Fig. 2, is a detail view of one of the supports.

30 Like characters of reference refer to like parts throughout the specification and drawings.

The apparatus consists of a perpendicular barrier *a* preferably of a triangular or 35 pyramidal shape, maintained in a substantially upright position by supports *b*.

Each of the supports *b* is of a substantially-triangular shape and is formed with a vertical slot *c*, into which enters a tongue *d* extending from the corresponding side of the barrier *a*, the barrier being provided 40 with battens *e* engaging the inner surface of the support to prevent its inward movement, and with a button *f* to prevent its outward movement, the battens and button forming a 45 guideway or fastening means by which the support can be removably secured to the barrier.

As shown in Fig. 1, the supports *b* are disposed at substantially right angles to the barrier *a*, and extend beyond the opposite sides thereof a sufficient distance to insure

the barrier being maintained in an upright position under ordinary conditions of use.

Each of the inclined edges of the barrier 55 *a* is formed with a series of steps *g*, *g'*.

Each of the steps *g*, *g'* is formed with a vertical socket *h* to receive a removable marker *i*, and the top of the supports *b* are formed with similar sockets *h'* for the same 60 purpose.

As shown in Fig. 1, the apex *j* of the barrier is truncated and is ornamented with a battlemented tower, the battlements *j'* of which are provided with vertical sockets 65 similar to those of the steps.

In the base of the barrier are apertures *k* for the flight of appropriate projectiles *l*, with which the game is played.

The markers shown in the accompanying 70 drawings are preferably flags, and any number of these flags can be employed. In the present instance, I have shown two sets of markers, each containing three flags, representing three players on each side. 75

Checkers may be employed as the projectiles, one set of players taking the checkers of one color, and the other side taking the checkers of the other color, the projectiles being directed at the apertures by the players in succession. 80

When a player succeeds in shooting a projectile through one of the apertures, he advances his flag upward along the stepped side until the battlement or step at the apex 85 of the barrier is attained. If his opponent shoots his projectile back through the barrier, his flag is retired down the stepped side.

Various rules may be adopted for governing the playing of the game, which it is 90 not necessary to elaborate in the present specification, and modifications may be made with regard to the shape of the barrier and to the method of supporting it, without departing from the principle of the invention, 95 as defined in the appended claims.

Having thus fully described the nature of my invention, what I claim as new and desire to secure by Letters Patent, is:—

1. A game apparatus comprising a perpendicular barrier of substantially pyramidal shape, means for supporting the barrier in upright position, markers for insertion in the inclined sides of the barrier, and ap-

ropriate projectiles, the base of the barrier being apertured for the flight of the projectiles therethrough.

2. A game apparatus comprising a perpendicular barrier of substantially pyramidal shape having apertures in its base for the flight of projectiles therethrough and having its inclined sides stepped with vertical sockets therein, markers for insertion

in said sockets, and appropriate projectiles 10 to be directed through the apertures in the base of said barrier.

Toronto, March 29th, 1916.

ARTHUR EDWARD VERRAL.

Signed in the presence of—

CHAS. H. RICHES,
EDWARD G. BERNSTEIN.
